ELECTRIC SECONDARY CLOCK

Roy M. Wilcox, Toronto, Ontario, Canada

Application May 13, 1940, Serial No. 334,688

4 Claims. (Cl. 58—26)

This invention relates to electric clock systems in which a master clock operates a number of secondary clocks by transmitting timed impulses from a source of electric current. Heretofore, due to the sensitiveness of the secondary clock mechanism, it has not been possible to use alternating current, as the latter sets up vibrations which seriously interfere with the regular and steady operation of the secondary clocks, and makes them noisy in operation. It has therefore been necessary to employ direct current to avoid these vibrations and noise.

The object of my invention is to devise an improved, quietly operating, secondary clock mechanism of a type which may be operated by ordinary commercial alternating current and in which any vibrations are limited so that they do not interfere with the operation of the clock mechanism.

I attain my object by providing suitable operating means for the secondary clock mechanism, such, for example, as a pawl and ratchet wheel mechanism, which operating means is in turn actuated by an electro-magnet of the plunger and solenoid type. This electromagnet includes an air-tight cylinder in which the armature reciprocates, said cylinder tending to slow up the inherent quick action of the armature due to the use of alternating current. I also provide resilient means for frictionally engaging the side of the ratchet wheel to steady the latter and thus prevent the coasting of the minute hand either forwards or backwards.

The improved mechanism is hereinafter more specifically described and illustrated in the accompanying drawing in which

Fig. 1 is a top view of the clock mechanism;

Fig. 2 a front view of the clock mechanism with the front plate removed, the solenoid and lower end of the armature being shown in section;

Figs. 3 and 4 detail views (looking from below) showing alternative forms of the connection between the armature and ratchet pawl; and

Fig. 5 a detail of the soldering contact for connecting the lead wires to the solenoid winding.

In the drawing like characters of reference indicate corresponding parts in the different figures.

A supporting frame is provided for the various parts and comprises a front plate 24 and a rear plate 25 connected together by spacer posts 40, 40^a and 40^b. Journalled in suitable bearings in the front and rear plates is a shaft 18, on which shaft is mounted the tubular shaft 21. The minute hand 18' is mounted on the shaft 18, while 55

the hour hand 21' is mounted on the tubular shaft 21.

The tubular shaft 21 is driven from the shaft 18 by means of the following speed reducing gearing. On the shaft 18 is a pinion 19 which engages a gear 23 on a short shaft. On this short shaft is a pinion 20 which engages a gear 22 on the tubular shaft 21.

The minute shaft 18 has mounted thereon a ratchet gear 17 by means of which it is driven. This ratchet gear is actuated by means of a pawl 15 having a hardened point 15^a engaging the gear teeth. This pawl 15 is pivotally connected at 12 with and is actuated by a lever 9 which is mounted on a shaft 13 rotating in holes in the front and back plates 25—24. The pin 12, it will be noted, is positioned close to the shaft 13, and is supported by the lever 9 and a disc 14, which are both attached to the shaft 13. The pawl 15 is held against the ratchet gear by the weight of the pawl arm 15^b. Counterclockwise rotation of the pawl is limited by a pawl shoulder 15^b coming against the shaft 13.

This lever 9 is in turn actuated by means of an electromagnet of the plunger and solenoid type. This electromagnet comprises a coil 2, which receives impulses from a master clock (not shown), 5 and 5^a being the terminals to which the leads from the master clock are connected. This coil is mounted between supports 6 and 6^a of insulating material supported between the front and rear plates 24 and 25. Within the coil 2 is positioned a cylinder 1 of non-magnetic material insulated from the coil 2 by a tube 3. In this cylinder reciprocates the piston armature 4, the outer end of which armature is connected to the lever 9 by a pin 7 and slot 30 connection. The piston armature 4 is a sufficiently close fit in the cylinder 1 so that when the armature is attracted into the coil, the air trapped in the cylinder 1 leaks out gradually thus slowing the armature on its inward travel. If the armature were not slowed down by said air trap, the armature would give the ratchet wheel and minute hand enough momentum to coast one or more extra teeth, thus putting the secondary clock out of step with the master clock. The said air trap also helps to dampen vibration of the armature 4.

The closed end of the cylinder 1 extends somewhat beyond the coil and its magnetic field, with the result that when the coil is energized and the armature is attracted into the coil, its momentum is checked directly by the air entrapped in the closed end of the cylinder and the inner end of the armature is spaced from the closed

end of the cylinder as indicated in dotted lines at 4^a, thus avoiding hammering or chattering of the piston armature against the cylinder end due to the vibrating magnetic pull of the coil 2.

A steel field piece 11 is mounted on the cylinder 1 at a point intermediate the end support 6 and closed end of said cylinder 1. This steel field piece 11 concentrates the magnetic field of the coil 2 so that the armature receives an almost steady pull up to the dotted line 4^a which indicates the practical limit of the magnetic field, consequently there is no magnetic pull beyond said line to cause the armature to move further inward after being checked by the air compression and the concentrated magnetic influence of the field piece 11 tends to hold the armature to the inward limit of movement, thus obviating a bouncing effect on the armature and ensuring a definite operating movement of the driving pawl.

A friction washer 26 and spring washer 27 are interposed between the ratchet wheel 17 and the rear plate, which washers exert a frictional steadyng effect on the ratchet wheel to prevent the minute hand coasting because of unbalance or momentum and to prevent the ratchet wheel being pulled back by the pawl 15. This type of steadyng means does not cause vibration of the armature 4, and does not wear the teeth of the ratchet wheel 17.

A stop rod 8 is mounted between the front and rear plates to limit the downward movement of the piston 4, and thus regulating the length of its stroke.

It will be evident, of course, that an ordinary pivot connection may be substituted for the pin and slot connection 7 in which case the solenoid as a whole may be pivotally mounted.

In Fig. 3 a modified arrangement of mounting the lever 9 and ratchet pawl 15 is shown. In this arrangement, a shaft 36 is carried by eccentrics 34 and 34^a, said shaft and eccentrics forming a part of the lever 9^a. The ratchet pawl 15 is pivoted on the shaft 36.

A further modification is shown in Fig. 4. The lever 9^b is mounted on a shaft 37 having eccentric pivots in the plates 24 and 25 and the ratchet pawl is mounted on the shaft 37.

In Figs. 5 and 1 is shown a method of securing the soldering contacts 5 and 5^a in place. This small, sheet-metal contact formed in a U-shape, is inserted through holes in the end piece 6 or 6^a. The ends of the contact are bent over and imbedded in the back of the coil end 6 so that they do not project and interfere with the winding of coil 2.

In operation, an impulse from the master clock energizes the coil 2, whose magnetism draws the armature 4 upward, thus rocking the lever and pushing the pawl 15 upwardly to rotate the

ratchet wheel 17. When the said impulse is ended, the armature drops downward under its own weight and the pawl point 16 drops into position to engage the next tooth of the ratchet wheel.

What I claim as my invention is:

1. In an electric secondary clock, the combination with the actuating shaft of the time indicators, of ratchet means for rotating said shaft, a solenoid type electro-magnet wound for an alternating current and having a tubular core extending above the magnetic field and closed at its upper end, and a piston armature operating in said tubular core and operatively connected with said ratchet means and cushioned at the upper end of its power stroke within said tubular core to offset the vibratory influence of the alternating current thereon during the period of flow of current through said solenoid.

2. In an electric secondary clock, the combination with the actuating shaft of the time indicators, of a solenoid type electro-magnet wound for alternating current and having an axial orifice therethrough, a cylinder of non-magnetic material arranged within said axial orifice having a closed end extending beyond its magnetic field, a piston armature operating in said cylinder and cushioned by the air entrapped in the closed end of said cylinder, and means operatively connected with said armature adapted to impart rotary movement to said actuating shaft.

3. In an electric secondary clock, the combination with the actuating shaft of the time indicators, of a solenoid type electro-magnet wound for alternating current having an axial orifice therethrough, a cylinder of non-magnetic material arranged within the axial orifice of said magnet and having a sealed end extending beyond the magnetic field, a piston armature operating in said cylinder, means connected with said armature for imparting rotary movement to said actuating shaft, and a magnetic field piece surrounding said cylinder between the solenoid and the sealed extremity thereof.

4. In an electric secondary clock, the combination with the actuating shaft of the time indicators, of a solenoid type electro-magnet wound for alternating current, a piston armature reciprocable in said magnet, a lever supported at one end on a fixed pivot and pivotally connected at the other end to said piston armature, a ratchet wheel mounted on said actuating shaft, a pawl pivotally mounted on said lever closely adjacent to the fixed pivot support thereof said pawl engaging said ratchet wheel to impart turning movement to said shaft, and means within said solenoid for offsetting the vibratory influence of the alternating current.

ROY M. WILCOX.
